Figur 1.

Inventor:

Max Müller

by his attorney

UNITED STATES PATENT OFFICE.

MAX MÜLLER, OF HAMBURG, GERMANY.

FLOATING DOCK.

Application filed March 30, 1922. Serial No. 548,232.

To all whom it may concern:

Be it known that I, MAX MÜLLER, a citizen of Hamburg, Germany, residing at Hamburg, Germany, have invented certain new 5 and useful Improvements in Floating Docks, of which the following is a specification.

The present invention has reference to improvements in floating docks and relates more particularly to a dock structure, essentially comprising two side pontoons and a middle pontoon in rigid connection, and the middle pontoon of less draft than that of the side pontoons. The middle pontoon is preferably in open communication with the 15 side pontoons and is automatically filled from, or emptied into, the side pontoons, as the case may be. The several pontoons may be suitably bulkheaded in longitudinal and transverse directions, in which case the middle pontoon compartments thus obtained, to the right of the longitudinal median bulkhead, will communicate with the respective right-hand side pontoon compartments, and those to the left of the median bulkhead 25 communicate with the respective left-hand side pontoon compartments, an arrangement which makes for readily controllable trimming of the dock.

My invention will best be understood when 30 described in connection with the accompanying drawings, in which Fig. 1 is a plan, and Fig. 2 a cross-section on line A—A of Fig. 1 of a dock of my improved design.

Similar letters refer to similar parts 35 throughout the several figures.

The central or middle pontoon *k* is subdivided by the longitudinal bulk-heads *a* *b* *c* into the compartments *e* *f* flanked by the side pontoons *d* and *g*. The cross-bulk-heads *h* 40 and *i* serve to ensure the stability of the floating dock in longitudinal direction. The line B—B (Fig. 2) indicates the inclined position the dock will take when the compartments *d* and *e* only are flooded or filled 45 up with water. The central bulk-head *b* is watertight throughout, whilst the lateral or outer bulk-heads *a* and *c* have water communicating openings *a*¹ and *c*¹, respectively.

50 The above described constructional form of the floating dock shows the following advantages.

When the dock is entirely freed from water and not loaded or weighted the receding lower or bottom wall of the compart-

ments *e* and *f* is some distance above the water level wherefrom it results that the resistance against moving the dock through the water is considerably reduced. In this elevated position a raft may be floated under 60 the middle pontoon in order to inspect and overhaul its bottom wall or to execute any other work of maintenance or restoring. The bottom wall of any of the side pontoons *d* and *g*, for example that of the side pontoon 65 *g*, may be brought out of the water, as indicated by the line B—B, by suitably trimming the dock by means of water-ballast let in at the opposite side only. By this way also the side pontoons may be easily 70 overhauled, repaired or repainted. Any contrivances for self-docking are therefore superfluous. From this results the further advantage that the strength of the dock in the longitudinal direction will be very great, 75 as the web of the dock is not anywhere interrupted.

The compartments *e* and *f* need no valves or like controlling devices, pumping out the water from the dock, the water contained 80 in the said compartments will run out or discharge automatically through the communicating openings in the outer bulk-heads *a* and *c*.

Owing to the fact that the whole bottom 85 is constructed to extend from side to side throughout the full breadth of the dock, a structure is obtained which is highly rigid also in the transverse or cross-direction.

The buoyancy of the compartments *e* and *f* 90 takes up a part of the weight of the vessel and relieves thereby the cross-beams in contradistinction to well known docks having non-buoying parts in the middle portion.

I claim:

1. In a floating dock of the character set forth, side pontoons and an intermediate pontoon, the latter in rigid communicating connection with said side pontoons and its bottom face extending in a plane substantially higher than that of the aligned bottom faces of said side pontoons. 95

2. In a floating dock of the character set forth, two side pontoons including upstanding walls, and a middle pontoon, the latter 100 rigidly communicatingly connected with said side pontoons and of substantially reduced vertical cross-section relative to that of said side pontoons, the deck of said middle pontoon extending in aligned continuation of the 110

respective side pontoon decks and its bottom plane raised above that of the bottoms of said side pontoons.

3. In a floating dock of the character set forth, a cellular pontoon structure, comprising two side compartments and intermediate compartments rigidly and communicatingly connected with the respectively contiguous side compartments, the upper faces of said compartments all alined to form a continuous deck and the bottom face of said intermediate compartments extending at a relatively higher level than the alined bottom faces of said side compartments.
- 10 4. In a floating dock of the character set forth, a cellular pontoon structure, comprising

ing cross-subdivided side compartments including upstanding walls, and a correspondingly cross-subdivided intermediate compartment, a centrally extending continuous longitudinal bulkhead in said intermediate compartment, and longitudinal ported bulkheads between said intermediate compartment and said side compartments, the tops of said compartments all extending in the same horizontal plane to form a continuous deck, and the bottom of said intermediate compartment extending at a substantially higher relative level than the bottoms of said side compartments. 30

In testimony whereof I affix my signature.

MAX MÜLLER. [L. s.]
